UNITED STATES PATENT OFFICE

CHARLES ERNST, OF NEW ORLEANS, LOUISIANA

LAWN CHAIR

Application filed February 25, 1930. Serial No. 431,221.

My invention relates to chairs, and more particularly to chairs of the adjustable or convertible type which are adapted for conversion into different types of chairs as well 5 as a couch, and consists in the combinations, constructions, and arrangements herein shown and described.

An object of my invention is to provide a chair of the type described which by easy 10 manipulations on the part of the operator may be adapted for rocking, for remaining stationary in what is known as an easy chair position, and for providing a horizontally extending plane for the reception of the reclining 15 body of an operator.

A further object of my invention is to provide a device of the type described which utilizes the force exerted by the weight of an operator to carry out the various operations 20 and which requires only a minimum of manual effort on the part of the operator to secure the chair in the various operative positions.

A further object of my invention is to provide 25 a device of the character described which has few parts, is simple to manufacture and does not get out of order easily.

Other objects and advantages will appear 30 as the specification proceeds and the invention will be more particularly defined in the appended claim.

My invention is illustrated in the accompanying drawings forming a part of this application, in which:

Figure 1 is an elevational view of the device in one operative position;

Figure 2 is an elevational view of the invention in another operative position;

Figure 3 is a further elevational view of 40 the device in still another operative position;

Figure 4 is a transverse sectional view, on line 4—4 of Figure 1, with parts thereof being shown in elevation;

Figure 5 is a sectional view, on line 5—5 45 of Figure 4; and

Figure 6 is a sectional detail view of a portion of the device, on line 6—6 of Figure 1.

In carrying out my invention I make use of a number of legs 1 which may be of any suitable construction and consist of any desired 50

number. These legs are connected to conventional rockers 2 which as in rocking chairs of usual construction may consist of a pair. The legs 1, as indicated at 3, are secured to a seating portion 4 thus supporting said seating portion 4 from the rockers 2. This seating portion extends between the legs 1 and projects rearwardly, as indicated at 5, to provide groove 6 for a purpose that will later be described. 55

Arm rests 7 are pivotally suspended above the seat 4 by means of the pivotally mounted back rest 8 which is swivelled to the seat portion, as shown at 9, and to said arm rests, as shown at 22, and the swivelly mounted foot rest 11, which is swivelled to the arm rests 7, as shown at 12, and to the seat, as shown at 13. The pivot members 22 include a lateral extension 10 projecting inwardly therefrom, to engage the notches 6 in the outer extremities 5 of the seat 4 to support the back and the rests when in one of the operative positions. 60

The back portion 8 may be of any suitable or conventional construction and need not differ from backs on ordinary chairs in any way except in the fact that it extends to a greater distance upwardly than the backs of ordinary chairs. In the preferred embodiment, this back rest or chair back 8 extends 65 above the head of the person operating the chair when seated therein. 70

The foot rest 11 consists of the downwardly extending members having positioned at their lower portion the foot rest proper 14 which is rigidly secured to said downwardly extending portions of the foot rest. This foot rest is provided with slats or other suitable wall forming means, not shown, which extend between the downwardly extending portions forming the sides or supports for said walls and the support for the portion 14. These downwardly extending members are the portions of the rests which are pivotally mounted to the opposite sides of the seat 4. The downwardly extended portions 15 and 16 are pivoted to the seat 4 in spaced relation therefrom. As shown most clearly in Figure 4 pin members 17 and 18 are provided upon the members 15 and 16 adapted for coopera- 75 80 85 90 95 100

tion with an operating member as will be hereinafter set forth. The foot rest 11 is provided with a bumper or buffer member 19 which is positioned opposite a similarly formed buffer or bumper member 20 on the forward legs of the chair. These bumper members provide an efficient means for taking up the shock incident to swivelly turning the rest 11 on the pivot members 17 and 18 toward the chair. This swivel turning is necessary in the operation of the device which will be more fully described as the specification proceeds.

For stopping the chair against rocking in certain of the positions thereof as well as to support the chair when the same is adapted to form a couch to accommodate the body of a reclining operator, I provide the arms 7 with rigidly mounted legs 20 and 21, which as shown in the preferred embodiment are crossed, but which may be mounted in any other manner adapted to perform the operation required. These chair legs 20 and 21 are rigidly secured to the arms 7, by the pivot members 22 and 23 respectively and are also rigidly secured to each other against relative movement, as shown at 24. The end portions 25 and 26 of these legs 20 and 21, respectively, are free as can be clearly seen. As will be later described, these free ends are adapted for engagement with the floor in certain positions.

For securing the chair in several of the adjusted positions and for permitting the operator to position the chair in other operative adaptations, the swivelly mounted adjusting bar 27 having a plurality of notches 28 at the outer extremity thereof is mounted on one of the arms 7, as clearly indicated at 29. This swivelly mounted adjusting bar 27 is adapted to engage one of the pivots 17 or 18 as desired to variably position the operating parts of the chair. It is obvious that the adjusting bar 27 could be duplicated on the opposite side of the chair or any other suitable arrangement as desired could be utilized.

A book rack 30 or any other receptacle desired for the use of the operator of the chair or other person may be mounted on the arm rests 7 as shown in Figures 1, 2, 3, and 6. When arranged in this position, the receptacle will be most conveniently located in any of the variable positions of the chair. It is obvious that the receptacle may be positioned at any other desired point. The chair may be provided with conventional rungs 1^a of any desired and suitable construction or may be braced in any other manner desired. This constitutes no part of my invention.

From the foregoing description, the use and operation of my device is easily understood. When the operator desires to use the chair as a rocker, the parts are positioned as

shown in Figure 1, the adjustable bar 27 having its innermost notch 28 engaged with the pivot 17. When thus positioned the foot rest extends substantially vertically downward in spaced relation to the front legs of 70 the chair while the back rest extends substantially vertically upwards. It will be noted from an examination of Figure 1 that the legs 20 and 21 in this position clear the operating surfaces of the rockers 2, which 75 engage the ground or other base upon which the chair is positioned for rocking. It can therefore be easily seen that the legs 20 and 21 are inoperative while the rockers 2 are operative. When the operator desires to use 80 the chair as an easy chair he forces his feet against the portion indicated at 31 of foot rest 11, thus throwing the arm rests forwardly relative to the seat 4 about the pivots 17 and 18. It can easily be seen that this decreases the distance between pivot 29 and pivot 17 which keeps the adjustable bar 85 engaged. It can also be easily seen that since the adjustable bar 27 is rigid it must give at one of the ends or at one of the points of 90 engagement with the pivot. The notches 28 are so formed that upon this relative movement of the arm rest 7 and the seat 4 the adjustable bar 27 rides upwardly on the pivot 17 or 18, thus disengaging the notch 28 which 95 has been holding the chair in position. The operator then relieves pressure of the heels or the rear part of his legs on the foot rest 11 below the pivot 13 and permits the arm rest 100 7 to slide backwardly relative to the seat 4 under pressure of the weight of the operator or under the force of gravity operating on said chair back through the pivot 22 connecting said back to the arm rest. He can then engage the adjustable rod 27 in any of the desired notches to fit the position of the feet or back to the position of Figure 1 or in the desired position shown in Figure 2. This is accomplished by merely engaging one of the notches 28 with the pivots 17 or 18 near 110 the outer extremity of the adjustable rod. When the chair is so positioned it will be obvious upon an examination of Figure 2 that the lower ends 25 of the rear legs 20 will project below the rockers 2 to engage the ground when the chair is rocked into the rearmost position and to thus stop the chair 115 in this position, and so provide a convertible chair of the type known as the easy chair.

When the operator desires to form a couch of the chair for receiving the reclining body of the operator he frees the adjustable bar 27 from the pivot 17 and by repeating the operation described in the preceding operation 120 or by forming the same from said pivot manually permits the back 8 to fall backwardly under the force of gravity or under pressure exerted by the back of the operator. The backward motion is controlled as to its veloc- 125

ity by means of the feet and legs of the operator, which by the exertion of pressure on the foot rest 11 may decelerate or accelerate the rate of fall of the back. The parts may thus be positioned in that adaptation shown in Figure 3, from an examination of which it will be disclosed that the lower extremities 25 and 26 of both the rearward and forward legs 20 and 21 respectively project below the rockers 22 and engage the ground. It will be noted that a portion 32 of the rockers 2 remain in engagement with the ground or other support adding to the supporting strength of the chair legs 20 and 21. It is also observed that in this position the back 8 with the rests 7 are supported by the pivots 10 which are further supported in the notches 6 formed in the backwardly extending portions 5 of the seat 4.

When the operator desires to throw the chair from the position shown in Figure 2 to that of Figure 1 or to other adjustable positions he simply throws the adjusting bar 27 over the pivots 17 or 18 manually and by pressure of his legs on the seat or by otherwise changing his center of gravity as regards the movable parts of the chair elevates the back and lowers the foot rest, permitting engagement of the notches 28 in the adjusting bar 27 for securing the chair in the desired position. It is thus seen that I have provided a chair which by easy manipulation on the part of an operator may be adapted to assume different positions from that of a chair of ordinary construction having rockers to that of a couch adapted for the reception of a reclining body of an operator. It is also obvious that the operation of the device may be accomplished by simple manual means taken in conjunction with the weight of the body of the operator. It can also be easily seen that the only manual means necessary for the operation of the chair is conveniently located, for engagement by the operator at all of the adjustable positions.

I claim:

In a reclining chair, a supporting base having a seat, a back rest pivotally mounted to said seat, said seat having a forwardly projecting portion and a rearwardly projecting portion, said rearwardly projecting portion having grooves formed therein, a foot rest, said foot rest comprising side members pivotally connected to said forwardly projecting portion of said seat and projecting thereabove, arm rests pivotally connected to respective projecting portions of said side members and to said back rest, rigid leg members connected to said arm rests and depending therefrom and movable with said arm rests to engage the supporting surface for said base when said back and foot rest are moved to a reclining position, and re-

spective pin members carried by said arm rests for engagement in said grooves for limiting backward movement of said back and arm rests.

CHAS. ERNST.
